UNITED STATES PATENT OFFICE.

ALONSON D. PERKINS, OF NEW YORK, N. Y.

PROTECTIVE SHUTTER FOR SHOP WINDOWS.

Application filed October 20, 1923. Serial No. 669,874.

The object of my invention is to provide a protective shutter for shop-windows, banks, and other display places or receptacles wherein valuable articles like furs, 5 jewelry, watches, etc. are exposed for sale or inspection,—which shall automatically close when the window, screen, curtain or other device interposed between the valuable articles and the persons looking at them, is disturbed or jarred. My invention is particularly valuable as a protection against that class of thieves who throw a halfbrick or stone through a plate glass window behind which articles of value are 10 displayed.

One form of my improved protective shutter is shown in the accompanying drawings in which:—

Figure 1, is a rear view of a shop window equipped with my protective shutter, which is up out of the way ready to fall when occasion arises.

Figure 2, is a side elevation.

Figure 3, is a detail of the shutter unrolled.

Figure 4, is a detail in elevation taken on line 4—4 on Figure 1, in the direction of the arrows.

Figure 5, is a horizontal section on line 5—5 of Figure 2.

Figures 6 and 7, are enlarged details taken from Figure 2.

Figure 8, is a detail of the eccentric detent.

Figure 9, is a diagrammatic view of mechanism for giving a visible and audible alarm by the falling of the shutter.

Same letters indicate similar parts on the different figures.

A, and A' are respectively the lower and upper sills of the window frame, each with an upright facing board, B, or B'. C, represents a plate glass window, behind which, as seen from the street, is arranged my protective shutter and its operating and supporting devices. This shutter, D, is shown rolled up on its drum E, in Figure 1, and unrolled in Figure 3. This drum is mounted in a suitable fixture F, on the window frame. The shutter D, is preferably made of slats of steel, a, a, properly secured and spaced by straps b, b, b,—as it is sufficient, for ordinary purposes of protection, that the shutter should be of a height great enough to prevent any attempt to reach over when down. Obviously, the longer

and higher the shutter, the greater the weight which has to be supported and rolled upon the drum.

G, G, are guide posts, preferably iron pipes, two on each side to form a runway for the shutter as shown best in Figure 5. Behind these posts is a rod H, held by and rotatable in brackets c, c, c. Upon the turning of this rod H, depends the sudden, 60 automatic, falling of the shutter and the simultaneous giving of an audible and visible alarm that the window has been tampered with. I, I, are buffers upon which the shutter strikes at the end of its fall and 65 upon which the shutter is held, against any attempt from the outside to raise it again, by means of the spring-controlled clutch K. L, is a handle equipped with suitable gearing M, and mounted in suitable bearings d, 70 for rolling up the shutter D on the drum E. J is a pawl for preventing the drum from slipping back during the rolling up of the shutter D, and L' is a handle for throwing 75 this pawl into and out of engagement.

The construction of the shutter,—its supporting devices and the means for raising the same, will, I think, be easily understood without further description. The remaining important features to be described are 80 those which are concerned with the release of the shutter when occasion arises from attempts at burglary, or the like.

The main object of this releasing device is that it should prevent the heavy curtain 85 or shutter D from unrolling at any time or from any other cause than the intended operation of the releasing device itself. While not in any way acting as a support of the weight of the shutter, the detent N, 90 performs the same function with regard to the drum E, on which the curtain or shutter D is rolled as a stone performs when placed under the lower edge of a wheel of a vehicle to prevent the same from rolling down hill. 95

This detent N, is mounted as an eccentric, by the pin e, in block f, on the top of the rod H, and at its forward end rests on the anti-friction roller g, mounted on the casting O, of the drum E. A guide h, through 100 which the detent N passes to and fro, is fastened to the top of the post G,—the play of the detent not being sufficient to let the detent escape from said guide h. The relation of the detent N, and the rod H, by 105 means of the eccentric form of the detent and the pin e, is such that a movement, say

a quarter turn, of the rod H in the proper direction will withdraw the detent from contact with the casting O, and thus permit the same to revolve under the pull of the 5 wound shutter D on drum E. This contact is simply a pressure contact between the forward point of the detent N, and a notch j, in the casting O, best shown in Figure 3, where the casting is shown upside down for 10 clearness.

To bring about this small movement of the rod H, I attach a number of screws or pins, k, k, at desired distances apart along the rod, and a similar row of pins or screws 15 on the opposite side of the window frame as l, l, l, so as to avail myself of the leverage created by the distance between the fixed points l, l, and the revolute points, k, k. A corresponding member of piano 20 wires, or other suitable connecting means, drawn taut, connect the pins k, with their corresponding fixed fulcrum points l, and experience shows that a very slight deflection of any one of these piano wires, laterally or vertically, is sufficient to pull the 25 rod H enough to cause it to revolve in the direction of this deflection, and thus release the detent N. The waiting shutter or curtain D at once plunges downward with 30 speed and violence, and, if of proper construction will catch and hold whatever is then in its downward path, whether a human hand, or arm, or any implement which may have been thrust through the window which 35 is protected by said shutter or curtain. In addition to the protection afforded by these piano wires, m, m, m, which are subjected to the slight necessary torsion by the breaking of the window pane, (as by a stone or 40 brick thrown therethrough) or an undue shaking of or pressure put upon said window, I further protect said window, or rather its contents of value, by what I call 45 a counter-protection, one form of which is illustrated at the bottom of Figure 1.

This counter-device is intended to be mounted in a convenient place behind the counter of the store in which the window is located and consists primarily of a support n, a lever o, a spring p, a connecting wire or chain q, pulley r, and torsion rod s. One end of this torsion rod is fixed as 50 at t, to the face board B, and the other end to the rod H, and its action when depressed by the lever o, in twisting the rod H, and releasing the detent N, is similar to that of the piano wires m, m.

Experience has shown that my improved 60 apparatus as thus described is very sensitive and responsive to any attempt to break or force open the window to which it is applied as a protective shutter, but is wholly

unresponsive to the ordinary jars and impulses which are not communicated through the agency of the piano wires m, m, or 65 rods s.

It will readily be understood that the release of the detent N, in the way stated will also cause an electric light P, and a call bell Q, to give the alarm that said window 70 has been tampered with. This is effected through proper wiring from the switch v, which, as shown best in Figure 2, consists of a stationary base-board 1, carrying stops 2, 3, between which swings the triangular 75 piece 4, pivoted thereto at 5. These parts (except the pivot) are preferably of insulating material. The triangular piece carries two contact-arms 6, 7, and the base-board carries two contact-points 8, 9, (latter 80 in dotted lines). In the position shown in the drawings the circuits are open, but these circuits are closed, to give the desired alarms, by causing the triangular piece 4, to swing away from the stop 3, to stop 2, 85 by the pull on fixed arm 10, of the wire 11. This movement of the triangular piece brings the contact-arms 6, 7, into contact with their respective contact-points 8, 9, and closes the two circuits to give the alarms. 90 The pull on the wire 11 is caused by the torsion of the rod H. This torsion is limited by the stop w, and the drum E is turned by the gear M, meshing with the gear M' on the drum shaft. 95

It is thought that the operation and advantages of my invention will be readily understood without further explanation.

I claim:—

1. A protective shutter for shop-windows 100 and the like, which comprises a gravity screen rolled upon a drum and held in check by a detent,—a detent mounted on a rotatable rod, and adapted to engage said drum,—without in any way supporting said 105 shutter,—a rotatable rod adapted to release said detent when itself partly rotated,—and means whereby a part rotation may be communicated to said rod to release said detent, and permit the unrolling of said screen 110 automatically.

2. A protective shutter for shop-windows and the like which comprises a detent adapted to retain and release the shutter, a rotatable rod adapted to move said detent 115 when itself partly rotated, and a number of piano wires tightly stretched in close proximity to the window to be protected, between a number of fixed points and a number of points on said rotatable rod whereby the 120 slightest deflection of any of said wires imparts to said rod the necessary part rotation to cause the release of said detent.

ALONSON D. PERKINS.
